Inventor
Attorney

UNITED STATES PATENT OFFICE.

CHARLES A. MEALY, OF PROVIDENCE, RHODE ISLAND, ASSIGNOR TO THE HADLEY COMPANY, OF PROVIDENCE, RHODE ISLAND.

WRIST-WATCH STRAP.

Application filed July 15, 1925. Serial No. 43,796.

To all whom it may concern:

Be it known that I, CHARLES A. MEALY, a citizen of the United States, residing at Providence, in the county of Providence and State of Rhode Island, have invented new and useful Improvements in Wrist-Watch Straps, of which the following is a specification.

This invention relates to certain new and useful improvements in wrist watch straps and the primary object thereof is to provide novel and improved means for enabling the strap to be lengthened so as to permit of disengagement thereof from the wrist without disconnecting the ends of the strap from the watch.

A further object of the invention is to provide means for enabling the strap to be easily and quickly adjusted as to length so as to fit wrists of different sizes and to also enable the strap to be likewise connected to and removed from the connecting means.

A further object of the invention is to provide novel means for latching the connecting means.

In the drawings:

Figure 1 is a top plan view of the invention;

Figure 2 is a side elevation;

Figure 3 is a view similar to Fig. 2 but showing the parts in extended position.

Figure 4 is a section on line 4-4 of Figure 1 and

Figure 5 is a section on line 5-5 of Fig. 1.

In proceeding in accordance with the present invention a strap composed of sections 1 and 2 is employed, the outer ends of which sections are connected to the watch and the inner ends of which are provided with loops 3 and 4.

The inner ends of the straps are spacedly connected by a connector composed of sections 5 and 6 hinged together at their ends at 7'. Section 6 has sides 7, between which section 5 is received, and section 5 further has a series of alined openings 8 in its sides 7".

A pin 9 having depressible spring tensioned ends 10 is projected through loops 3 and its ends are receivable in a selected pair of the alined openings 8 so as to enable the section 1 to be adjustably connected to the connector section 5 at various points along the length of the latter section. A similar

pin 11 having depressible spring tensioned ends 12 is secured to the section 6 and is passed through the loop 4. By use of the pins with depressible ends, it will be seen that each strap section may be easily and quickly applied to and removed from the connector.

The sides 7 of the connector section 5 are further formed with outwardly struck keepers 10' into which the spring tensioned ends 12 of the pin 11 snap, whereby to latch the connector sections together. This pin 11 functions in a dual capacity in that it connects the strap to one connector section and the latter to the other connector section.

The connector sections preferably are apertured to lighten same and to afford ventilation. The strap section 1 is further held by and between the sides 7" of connector section 5.

From the foregoing it will be seen that in order to expand or lengthen the strap it is merely necessary to pull outwardly on the section 6 to disengage its pin from the keepers 10' whereupon the connector sections are swung apart about hinge 7', thus expanding or lengthening the strap, and enabling the same to be easily removed from the wrist.

Having thus described my invention what I claim as new and desire to secure by Letters Patent is:

1. In a wrist watch strap, a pair of straps having loops at their inner ends, a pair of hingedly connected connector sections, pins passed through the strap loops and having spring tensioned ends removably disposed in perforations provided therefor in the connector sections, each connector section having sides, the strap of one section being received between the sides of the latter and the said section itself being received between the sides of the other section and keepers in the sides of the said last named section to receive the ends of the pin of the other sections.

2. In a wrist watch strap, a pair of straps, a pair of connector sections hinged together at their inner ends and connected to the respective straps at their outer ends, said sections having sides, one section receiving its strap between its sides and the latter section being received between the sides of the other section, and means to latch the

sections together including keepers on the sides of one section, and a pin securing the strap of the other section thereto and formed to have its ends snap into the keepers.

5. 3. In a wrist watch strap, a pair of straps, a pair of connector sections hinged together at their inner ends and connected

to the respective straps at their outer ends, keepers on one section and a pin securing the strap of the other section thereto and 10 formed to snap into the keepers.

In testimony whereof I have signed my name to this specification.

CHARLES A. MEALY.
